FUSE FOR PROJECTILES

Alfred F. Teitscheid, Wharten, N. J.

Application June 6, 1934, Serial No. 729,249

6 Claims. (Cl. 102—39)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a fuse for projectiles and more particularly it has reference to a unit carrying centrifugally releasable bolts.

In fuses for artillery projectiles a common practice of assuring safety of the firing mechanism consists in maintaining one or more of the 10 elements of the mechanism in unarmed position by means of bolts or pins adapted to be moved under the influence of centrifugal force during flight of the projectile. The situation frequently occurs, especially in low angle impact and in projectiles having low rotational velocities, that the bolts when no longer subject to the influence of centrifugal force reengages the elements of the firing mechanism before such elements can 15 function.

20 The purpose of this invention is to provide a separate bolt-carrying unit which may be readily applied to a fuse casing and associated with a firing mechanism and which includes means for opposing return of the bolts to unarmed or safety 25 position when the bolts have once been moved to armed position.

To these and other ends, the invention consists in the construction, arrangement and combination of elements described hereinafter and pointed out in the claims forming a part of this 30 specification.

A practical embodiment of the invention is illustrated in the accompanying drawing, 35 wherein:

Fig. 1 is a longitudinal sectional view of a base fuse provided with the improved bolt unit and showing the parts in unarmed position.

Fig. 2 is a similar fragmentary view showing 40 the parts in armed position.

Figs. 3 and 4 are (enlarged) detail sectional views on the corresponding lines of Figs. 1 and 2.

Fig. 5 is a sectional view on the line 5—5 of Fig. 3.

45 Fig. 6 is a longitudinal sectional view showing the application of the invention to a nose fuse.

Referring to Figs. 1 to 5 there is shown a base fuse comprising a body 5 having an explosive train chamber 6 and a firing pin chamber 7, the latter closed by a plug 8.

A thimble 9 in the chamber 6 and threadedly secured to the body carries an explosive train which in the illustration includes a primer 10, a delay train 11 and a detonator 12. The detonator extends into a booster charge 13 contained in a cup 14 secured to the body 5.

A plunger 15 normally positioned in the rear part of the chamber 7 carries a firing pin 16 projecting from the front face of the plunger and having a point 17 on its front end.

A block 18 positioned in the front part of the chamber 7 is held against a shoulder 19 of the body by means of a sleeve 20 surrounding the plunger and seated on the plug 8. A coil spring 21 confined between the plunger and the block 15 normally holds the plunger in the rear part of the chamber 7 against the plug 8.

The block 18 is formed with an axially disposed aperture 22, a diametrical passage 23 and a radial slot 24 which is disposed perpendicularly 20 to the passage 23. The aperture 22 is provided to permit passage of the firing pin 16, the front end 17 of which is normally inserted in the aperture.

A pair of bolts 25—25 are slidably mounted in 25 the passage 23 on opposite sides of the axis of the block. A spring 26 confined between each of the bolts and a shell 27 embracing the block 18, normally urges the bolt into the axial aperture 22 and into the path of movement of the firing pin, 30 The inward movement of the bolts under the action of their springs is limited by the point 17 of the firing pin.

Referring to Figs. 3—5, a tumbler 28 is disposed in the slot 24 and is pivotally mounted on a pin 35 35 carried by the block 18. The tumbler is mounted off-center on the pin to provide a long or heavy arm 30 and a short or light arm 31 and this unbalanced relation is made more pronounced by forming the short arm with tapered 40 walls 32—32 to reduce its mass. The short arm 31 of the tumbler is formed with a recess 33 in its end to permit passage of the firing pin when the tumbler is in a position perpendicular to the axis of the firing pin. The tumbler is so arranged 45 that in the foregoing position the short arm will be in the path of return movement of the bolts 25 when the bolts are in the armed position shown in Fig. 4.

50 A stop member 34 for engaging the long arm

30 of the tumbler and limiting movement of the tumbler to a horizontal position is conveniently formed by cutting the closed end 35 of the shell 27 and bending the cut-out portion inwardly into 5 the slot 24.

The shell 27 forms a container for the block and has an inturned flange 36 for confining a disc 37. The closed end 35 of the shell and the disc 37 are provided respectively with apertures 38 10 and 39 to permit passage of the firing pin.

In the nose fuse shown in Fig. 6 the block 40, carrying an element 41 of an explosive train and also centrifugally releasable bolts 42-42, is mounted for movement as a plunger. It is held 15 in rearmost position by a spring 43 and by a firing pin 44 directly engaging the bolts 42.

The operation of the base fuse shown in Figs. 1-5 is as follows: When a projectile equipped 20 with the fuse is fired from a gun and is in flight, the bolts 25 move outwardly under the influence of centrifugal force. The tumbler 28 is likewise under the influence of centrifugal force and swings to a position perpendicular to the longitudinal axis of the fuse with its heavy or long arm 25 30 arrested by the stop member 34 and its light or short arm 31 disposed in the passage 23 in position to oppose return movement of the bolts 25. On impact the tumbler is maintained in position due to inertia. The plunger 15 moves forwardly due to its inertia and the firing pin carried by the plunger actuates the primer.

I claim:

1. In a fuse, a casing having a chamber, a block in one end of the chamber, said block formed 35 with an axial aperture, a diametrical passage and a radial slot, centrifugally releasable bolts mounted in the passage of the block and normally obstructing the axial aperture, a tumbler pivotally mounted in the radial slot of the block and having a light arm and a heavy arm, the end of the light arm being recessed, said tumbler positioned so that its light arm is movable into the diametrical passage to oppose return movement of the bolts, a stop member carried by the block and engageable by the heavy arm of the tumbler, a 40 plunger in the other end of the chamber, a spring between the block and plunger, and a firing pin carried by the plunger and movable through the axial aperture of the block upon displacement of the plunger.

2. In a fuse, a casing having a chamber, a block in one end of the chamber, said block formed with an axial aperture, a diametrical passage and a radial slot, centrifugally releasable 45 bolts mounted in the passage of the block and nor-

mally obstructing the axial aperture, a centrifugally operable member in the radial slot and movable into the diametrical passage to oppose return movement of the bolts, a plunger in the other end of the chamber, a spring between the 5 block and plunger, and a firing pin carried by the plunger and movable through the axial aperture of the block upon displacement of the plunger.

3. A unit for a fuse comprising a shell, a block within the shell, said block formed with an axial 10 aperture and with a diametrical passage and a radial slot closed by the shell, centrifugally releasable bolts mounted in the passage of the block and normally obstructing the axial aperture, a tumbler pivotally mounted in the radial slot of the 15 block and having a light arm and a heavy arm, the end of the light arm being recessed, said tumbler positioned so that its light arm is movable into the diametrical passage to oppose return movement of the bolts, and a stop member 20 on the shell and engageable by the heavy arm of the tumbler.

4. A unit for a fuse comprising a shell, a block within the shell, said block formed with an axial 25 aperture and with a diametrical passage and a radial slot closed by the shell, centrifugally releasable bolts mounted in the passage of the block and normally obstructing the axial aperture, a centrifugally operable member in the radial slot and movable into the diametrical passage 30 to oppose return movement of the bolts, and a stop member on the shell engageable by said centrifugally operable member.

5. A unit for a fuse comprising a block formed with an axial aperture, a diametrical passage and a radial slot centrifugally releasable bolts mounted in the passage of the block and normally obstructing the axial aperture, a tumbler pivotally mounted in the radial slot of the block and having a light arm and a heavy arm, the end of the 40 light arm being recessed, said tumbler positioned so that its light arm is movable into the diametrical passage to oppose return movement of the bolts, and a stop member carried by the bolt and engageable by the heavy arm of the tumbler. 45

6. A unit for a fuse comprising a block formed with an axial aperture, a diametrical passage and a radial slot, centrifugally releasable bolts mounted in the passage of the block and normally obstructing the axial aperture, and a centrifugally operable member in the radial slot and movable into the diametrical passage to oppose return movement of the bolts. 50
